UNITED STATES PATENT OFFICE.

ANDREW E. MCKAY, OF WILBUR, WASHINGTON.

WEEDEER.

1,210,092.

Specification of Letters Patent. Patented Dec. 26, 1916.

Application filed March 20, 1916. Serial No. 85,521.

To all whom it may concern:

Be it known that I, ANDREW E. MCKAY, a citizen of the United States, residing at Wilbur, in the county of Lincoln and State 5 of Washington, have invented a certain new and useful Improvement in Weeders, of which the following is a specification.

My invention relates to improvements in weeders of that class which is employed in 10 the operation of uprooting and destroying weeds growing in cultivated fields, and the object of my invention is to provide a weeder which shall be efficient in its operation and simple in its plan of construction, 15 and which shall be adapted to be drawn over the surface of the field to be weeded.

A further object of my invention is to 20 provide such a weeder which shall have a seat upon which the operator may ride, and 25 which shall embody a plurality of reciprocally movable series of earth-engaging blades associated with mechanism that is adapted to be controlled by said operator whereby all of said blades may be adjust- 30 ably raised and lowered to project them into the earth for different distances at different times or wholly to disengage them from said earth as may be required. I accomplish these objects by devices illustrated in the 35 accompanying drawings, wherein—

Figure 1 is a plan view of a weeder embodying my invention; Fig. 2 is a view of the same in side elevation with the nearer wheel removed; Fig. 3 is a view of parts of 35 the same in vertical section on broken line x, x of Fig. 2.

Referring to the drawings, throughout 40 which like reference numerals designate like parts, an iron frame is made of channel iron comprising oppositely disposed side rails 4 and 5 which extend for a greater portion of 45 their length in parallel lines and whose rearward end portions are bent directly downward to form oppositely disposed vertical side rails 6 and 7 respectively, while their 50 forward end portions extend forwardly from their parallel portions in converging lines to a block 8 to which they are secured by bolts (as bolts 9 shown in Fig. 2) which 55 block 8 is provided with an integral downwardly extended portion 60 whose lower end rests upon a fifth-wheel 10 which is provided with a king-bolt 11 that extends upwardly through said block 8 thus to make a swiveled connection between said block 8 and said fifth-wheel 10, which fifth-wheel

10 is secured to the central portion of an axle 12 which is provided with truck wheels 13 and 14.

Disposed to extend between the side rails 4 and 5 are cross-braces 15 and 16, as shown more clearly in Fig. 1, and mounted upon the cross-brace 16 at the rearward end of the structure is a seat 17 that may be occupied by an operator.

Secured to the underside of each of the side rails 4 and 5, at opposite points adjacent to the forward side of the cross-brace 16, is an axle bearing, as axle bearings 18 and 19 respectively, within which is rotatably disposed an axle 20, as more clearly shown in Fig. 3, upon each of the opposite end portions of which is securely mounted a wheel, as wheels 21 and 22, the peripheries of which wheels 21 and 22 are provided with a plurality of ridges, as ridges 23, disposed at equi-distant points therearound, which ridges 23 serve in a well known manner to engage with the surface of the ground to insure a rotation of said wheels 21 and 22 thus to rotate the axle 20 as the structure is drawn over said surface of the ground.

Swingingly mounted on the axle 20 are suspension links 24 and 25, the link 24 being disposed adjacent to the outer side of the bearing 18 where it is confined with respect to sidewise movements by a collar 26, while link 25 is disposed adjacent to the outer side of the bearing 19 where it is confined with respect to sidewise movements by the hub 90 of a gearwheel 27 which is mounted freely on said axle 20 adjacent to the outer side of said link 25.

In the lower end portion of each of the links 24 and 25 is formed a bearing within 95 which is rotatably disposed one of the opposite end portions 28 and 29, respectively, of a quadruple crank-shaft which is provided with cranks 30, 31, 32 and 33, as shown more clearly in Fig. 3.

On the outwardly projecting end portion 29 adjacent to the outer side of the link 25 is secured a pinion 34 whose teeth engage with the teeth of the gearwheel 27, whereby said crank-shaft with its cranks 30, 31, 32 and 33 will be rotated in response to a rotation of said gearwheel 27. Articulated with said crank-shaft, at points thereon adjacent to the inner side of the link 24 and the inner side of the link 25 respectively, are the rear end portions of the opposite side rails, respectively, of a rectangular frame 35

whose forward end portions, in a similar manner, are articulated to another quadruple crank-shaft 36 which is rotatably mounted in bearings formed in the lower end portions of suspension links 37 and 38 whose upper end portions are attached to a shaft 39 which is rotatably mounted in brackets (as bracket 40 shown in Fig. 2) secured to the under side of the forward end of the parallel portions of the side rails 4 and 5, whereby said rectangular frame 35 is suspended to be swingingly movable, always in a horizontal plane, from its position shown by full lines to its position shown by broken lines in Fig. 2.

The four cranks of the forward crank-shaft 36 correspond in shapes and positions to the cranks 30, 31, 32 and 33 of the rearward crank-shaft and articulated with each of the cranks 30, 31, 32 and 33 is the rearward end portion of a connecting rod comprising two parallel bars (as connecting rods 41, 42, 43 and 44 shown more clearly in Fig. 1) whose forward end portion is articulated to the opposite corresponding one of the cranks of the crank-shaft 36, whereby a revolution of the cranks 30, 31, 32 and 33 will communicate a corresponding rotary motion to the crank-shaft 36 in a well known manner.

Fastened at equi-distant points on each of the connecting bars 41, 42, 43 and 44, to extend downwardly therefrom, are four blades, as blades 45, 46, 47 and 48 respectively, of a form to adapt them to uproot or destroy weeds disposed in their several paths.

Freely mounted on the axle 20 is a sleeve 49 on one end portion of which is an integral arm 50 whose lower end portion is articulated with the rearward crank-shaft at a point between cranks 32 and 33, while to the other end portion of said sleeve 49 is secured a hand-lever 51 which extends upwardly to adapt it to be manipulated by the occupant of the seat 17. The hand-lever 51 is provided with a well known form of detent 52 that is adapted to engage with a desired one of a plurality of notches formed in the periphery of a quadrant 53 which is secured to the cross-brace 16 at a point to adapt it to engage with said detent 52 whereby said hand-lever 51 may be maintained at a desired one of different angular positions. Thus, it is manifest that when said hand-lever 51 is moved forward to its position shown in Fig. 2 then the frame 35 will be in its lowest position to project the blades 45, 46, 47 and 48 into the earth for a maximum distance, and when said hand-lever 51 is drawn rearwardly to its farthest extent then said frame 35 will be raised to its position shown by broken lines in Fig. 2 whereby said blades will be disengaged

65 from the earth, and by disposing said hand-

lever 51 with its detent engaged with the proper one of the notches of the quadrant 53 said frame 35 may be disposed at a required elevation to cause said blades to operate in the earth at a desired depth.

In order to communicate rotary motion from the axle 20 to the gearwheel 27 at desired times as the weeder is drawn over a field, thereby to rotate the crank-shafts and operate the blades 45, 46, 47 and 48, I have provided a clutch member 54 of well known form which is slidably mounted and keyed on the axle 20 so that it may be movable in a lengthwise direction thereon but not in a circumferential direction with respect thereto, whereby it may be caused to engage and disengage, as may be required, with teeth provided on the outer side of the hub of the gearwheel 27.

The hub of the clutch member 54 is provided with a groove within which is freely disposed a ring 55 made of two separable parts to which ring 55 is articulated one end of an arm 56 whose other end is mounted securely on the lower end of a vertical shaft 57 which is rotatively movable in a bearing formed in a bracket 58, the upper end portion of said shaft 57 being provided with a hand-lever 59 that extends upwardly and rearwardly to adapt it to be accessible to the right hand of the occupant of the seat 17.

In an obvious manner, a manipulation of the hand-lever 59 may operate the clutch member 54 to control the communication of rotary motion from the axle 20 to the pinion 29 and the crank-shaft upon which said pinion 29 is mounted.

In the operation of a weeder embodying that form of my invention which I have illustrated and described, as the weeder is drawn over the field to be weeded the hand-lever 51 is disposed at a required angle to cause the blades 45, 46, 47 and 48 to project into the earth for a desired distance to catch the roots of weeds, rotary motion having been communicated to the crank-shafts by a manipulation of the hand lever 59, whereupon the connecting rods 41, 42, 43 and 44 will be moved forward and backward by the action of their respective cranks in such manner that during their forward movements they will dig into the earth and while beneath the surface of the earth such forward movement will be accelerated by the forward movement of the whole weeder, and near the termination of such forward movement said blades will be raised out of the earth and then move freely backward to their rearwardmost point when they will again be moved downwardly into the earth to repeat their forward movement in time to prevent skipping any portion of the respective paths of said blades.

I have shown crank-shafts having four

cranks and four connecting rods having each four blades but such numbers may be increased or diminished as may be desired for different conditions of operation.

5 Of course, my weeder may be drawn by horses, traction engines, or cables actuated by any form of motor, and changes may be made in the forms, dimensions and arrangement of parts thereof without departing from the spirit of my invention.

What I claim is:

1. In a weeder of the class described, the combination with a frame, of a truck whose axle is disposed to support the forward end 15 of said frame; a second truck whose axle is rotatably associated with the rearward portion of said frame and whose wheels are rigidly secured to its said axle; two suspension links freely suspended by the axle of said 20 second truck and disposed normally to extend downwardly each from a point thereon adjacent to a different one of the opposite side rails of said frame; a crank-shaft rotatably mounted in the lower end portions 25 of said links, said crank-shaft being provided with a plurality of off-set cranks; a pinion securely mounted on one end of said crank-shaft; a gearwheel freely mounted on the axle of said second truck and disposed 30 to engage with said pinion, said gearwheel being provided with a hub having sidewise projecting teeth; a lever-actuated clutch member mounted on said axle of said truck and adapted operatively to engage 35 and disengage the teeth of the hub of said gearwheel; mechanism, including a hand-lever, associated with said axle of said second truck and with said crank-shaft whereby said crank-shaft may be swingingly 40 moved to and be secured in a desired angular position; two additional suspension links disposed with their upper end portions pivotally connected each with a forward portion of a different one of the opposite 45 side rails of said frame; a second crank-shaft having off-set cranks corresponding in shape and numbers to the off-set cranks of

said first named crank-shaft, and being rotatably mounted in the lower end portions of said additional suspension links; a rectangular connecting frame having its rearward end portion articulated with said first named crank-shaft, and its forward end portion articulated with said second named crank-shaft; blade-supporting bars disposed each with one of its end portions articulated to a different one of the off-set cranks of said first named crank-shaft, and with its other end portion articulated with the corresponding one of the off-set cranks 50 of said second named crank-shafts; and blades attached to said blade-supporting bars to extend downwardly therefrom.

2. A weeder of the class described, which embodies a frame mounted on a forward truck and a rearward truck, the axle of said rearward truck being rotatable with respect to said frame and the wheels of said rearward truck being rigidly attached to its axle; a pair of suspension bars swingingly 65 attached to the axle of said rearward truck to extend downwardly therefrom; a second pair of suspension bars swingingly attached to a forward portion of the side rails of said frame to extend downwardly therefrom; 70 a separate crank-shaft provided with a plurality of off-set cranks rotatably mounted in the lower portions of each of said pairs of suspension bars; separate blade-carrying connecting bars having their 75 opposite ends articulated with respectively corresponding ones of the off-set cranks of said crank-shafts; blades rigidly attached to said blade-carrying connecting bars to extend downwardly therefrom; and controllable means for communicating rotary motion 80 from the axle of said rearward truck to the adjacent one of said crank-shafts.

In witness whereof, I hereunto subscribe my name this 10 day of March A. D., 1916. 90
ANDREW E. MCKAY.
